ATTORNEY.

UNITED STATES PATENT OFFICE.

AUGUSTUS ALBERT WEST, OF NEW YORK, N. Y., ASSIGNOR TO WEST ELECTRIC HAIR CURLER CO., OF PHILADELPHIA, PENNSYLVANIA, A CORPORATION OF NEW YORK.

HAIR-CURLER.

1,082,784.

Specification of Letters Patent.

Patented Dec. 30, 1913.

Application filed March 4, 1912. Serial No. 681,551.

To all whom it may concern:

Be it known that I, AUGUSTUS ALBERT WEST, a citizen of the United States, and a resident of the borough of Brooklyn, county of Kings, city and State of New York, have invented certain new and useful Improvements in Hair-Curlers, of which the following is a specification.

The subject of this invention is designed 10 as an important improvement in means for operating or disengaging the locking parts of hair curlers that are secured by latching, or those that are so constructed that certain of their parts are secured together by 15 a transverse motion. In my experiments with this improvement I have employed a curler such as was patented to me some time since, but I do not wish it understood that I confine this invention to this particular curler nor in fact to any particular curler as I have found that it operates 20 equally well with any of the numerous devices in this general class. I have found that there is a decided objection to these 25 curlers because it is found that a continued operation of them will cause a slight soreness of the operating thumb and fingers, and it is to overcome this objection that I have designed and executed this improvement, which is intended to facilitate the 30 operation and enhance the value of a previous hair curler patented to me March 28th, 1905, Serial #785,844.

The following is what I consider the best 35 means of carrying out this invention.

The accompanying drawings form a part of this specification, in which—

Figure 1 shows in plan view a curler provided with my improvement. Fig. 2 shows 40 in elevation the curler shown in Fig. 1, though in this view the parts of the curler are disengaged. Fig. 3 shows the method of operating, the hand of the operator being indicated in dotted lines. Fig. 4 shows a 45 modification of the structure and Fig. 5 shows this modified structure as a part of a curler of somewhat different construction.

Similar reference numerals indicate like 50 parts in all the figures where they appear. Referring to Figs. 1 and 2, at 1 I have shown the body portion of a curler provided with a hooked end 2 in which is produced a notch 3. An eye or loop 4 connects the tongue 5, with the body portion and a reduced extension 6 of the tongue 5 is in-

tended to pass into the loop 2 and be engaged by the notch 3. All of these parts are of ordinary construction and operate in a well known manner unlatching by a downward and transverse pressure of a finger 60 placed against the part 5, at a point closely adjacent to the loop 2 while the body 1 is supported by the hand of the operator.

As the parts of this curler must necessarily be made thin to obtain sufficient 65 lightness and yet strong to operate with a desirable degree of satisfaction, it is found that the use of a number of these devices one after another will cause a temporary soreness to the finger of the operator, I 70 have therefore placed a hump 7 at the point where the pressing finger or thumb will engage with the part 5 to unlock it, and I have so proportioned this hump so that it does not in any way interfere with the 75 operation of the device, the hair usually wound about the tongue member 5 passing over the hump 7, without interference of any kind. The hump 7 may be formed from a piece 80 of solder or softer metal secured upon the upper side of the tongue member 5, or it may be an elongated rib 8 punched or shaped from the tongue proper by having a portion of the metal from which the tongue is formed pressed upward or outward 85 out of the plane of the tongue as shown in Figs. 4 and 5. This construction shown in Figs. 4 and 5 may be the preferable one as it does not limit the pressure receiving space nor demand that the fingers 90 of the operator shall be placed at any particular point along the tongue 5. The hump or raised portion 7 shown in Figs. 1 and 2 may also be formed by pressing upward a portion of the metal of the tongue 5 and 95 other modifications within the scope of the appended claim may be made without departing from the principle or sacrificing the advantages of this invention.

Having carefully and fully described my 100 invention what I claim and desire to secure by Letters Patent is:

A new article of manufacture consisting of a curler having a part thereof hingedly connected and adapted to be latched to another part and adapted to be disengaged from said latched action by a depressing and a transverse motion, said hingedly connected part being provided with a smoothly rounded portion extending upward out of 110

2
the plane of the part and arranged along
the central longitudinal line of the part be-
tween said hinged connection and the latch-
ing end of said member and away from the
edges thereof to assist in the operation of
the part as herein specified.

Signed at New York city, in the county

of New York, and State of New York, this
19th day of February 1912.

AUGUSTUS ALBERT WEST.
